UNITED STATES PATENT OFFICE

100,297

DESIGN FOR A COMBINATION TRAVELING AND DESK CLOCK

Max Schlenker, La Salle, Ill., assignor to Western
Clock Company, Peru, Ill., a corporation of
Illinois

Application March 5, 1936, Serial No. 61,489

Term of patent 14 years

To all whom it may concern:

Be it known that I, Max Schlenker, a citizen of the United States, residing in the city of La Salle, in the county of La Salle and State of Illinois, have invented a new, original, and ornamental Design for a Combination Traveling and Desk Clock, of which the following is a specification, reference being had to the accompanying drawing, forming a part thereof.

In the drawing:

Fig. 1 is a front view of the combination traveling and desk clock showing my design with the protective covering pushed aside exposing the clock dial and hands.

Fig. 2 is a side view of same which shows the rear covering part used as a foot to support the clock on the desk top.

Fig. 3 is a front view of the combination traveling and desk clock with the protective covering moved in position to cover the clock parts shown exposed in Fig. 1.

Fig. 4 is a plan view of my design shown in Fig. 3.

I claim:

The ornamental design for a combination traveling and desk clock as shown and described.

MAX SCHLENKER.
